Patented July 19, 1921.

UNITED STATES PATENT OFFICE.

LEMUEL R. JONES, OF LOS ANGELES, CALIFORNIA.

ENVELOP.

1,384,837.

Specification of Letters Patent. Patented July 19, 1921.

Application filed March 8, 1920. Serial No. 364,167.

To all whom it may concern:

Be it known that I, LEMUEL R. JONES, a citizen of the United States, residing at Los Angeles, in the county of Los Angeles and State of California, have invented new and useful Improvements in Envelops, of which the following is a specification.

This invention relates to an envelop and particularly pertains to a closure therefor.

10 It is the object of this invention to provide an envelop closure embodying a flap and means for detachably fastening the flap in a closed position in which the use of metallic eyelets, clips and the like are dispensed with 15 and which obviates the use of strings and similar fastenings.

Another object is to provide a flap fastener for envelopes and the like which may be formed wholly of paper or material of 20 like nature, and which fastener is so constructed as to afford a substantial engagement with the flap to securely hold the latter in a closed position without danger of being accidentally disengaged yet which may be 25 easily and quickly disposed in and out of its fastening position.

Another object is to provide a flap fastener of the above character which may be economically manufactured and readily applied to an envelop or the like.

30 Other objects will appear hereinafter.

The invention is illustrated in the accompanying drawings in which:

Figure 1 is a plan view of a portion of an 35 envelop and flap showing the fastener as applied and in its unfastened position with the envelop flap open;

Fig. 2 is a similar view showing the envelop flap closed and secured by the fastener;

Fig. 3 is a detail in perspective illustrating the initial step employed in fastening the flap;

Fig. 4 is a detail in perspective showing 45 the manner of connecting the fastener to the flap and disengaging it therefrom.

More specifically 5 indicates the body of an envelop and 6 denotes the flap portion thereof. In carrying out the preferred embodiment of my invention the flap is provided with a slot 7 which is preferably formed in a reinforcing strip 8 of fiber board or other suitable material, which strip is here shown as bent around the edge of the flap to extend over the opposite faces thereof and secured in place by a suitable adhesive.

The reinforcing strip may however extend over one side only of the flap and where the material of which the flap is formed is of sufficient strength the reinforcing strip may 60 be dispensed with.

Mounted on the envelop body is a tongue 9 adapted to project through the slot 7 in the flap when the latter is in its closed position and which tongue is formed at its 65 outer end with oppositely extending ears 10 and 11 having a combined length greater than that of the slot so that when the end of the tongue is inserted through the slot the ears will project laterally beyond the 70 ends of the slot to effect a buttoning engagement therewith.

As a means for providing a construction whereby the tongue may be readily contracted to permit the insertion of its outer 75 end through the slot and its removal therefrom, the tongue is formed with a longitudinal slit 12 the outer end of which flares outwardly and opens at the end of the tongue and the inner end of which terminates in spaced relation to the inner end of the tongue, this slit dividing the tongue into two members 14 and 15 adapted to be overlapped at their outer ends. The tongue is 80 preferably formed by being struck from a blank 16 of fiber board or similar material which blank is secured to the envelop by a suitable adhesive, but in some instances the tongue may be struck from the material of which the envelop is formed. As a means 85 for facilitating bending of the tongue relative to its blank the point of juncture of the tongue and blank is formed with a straight transverse score 17 and in order to facilitate overlapping the outer ends of the tongue 90 portions 14 and 15 diagonal scores 18 and 19 are formed in the base portion of the tongue and extend diagonally from the base of the slit 12 to the ends of the score 17. A triangular body 20 is thus formed in the space 100 bounded by the scores which constitutes the inner portion of the tongue and is hinged to the blank and on the diagonal edges of which the two tongue members 14 and 15 are hinged.

105 As a means for facilitating the manipulation of the tongue in engaging it with the flap and disengaging it therefrom the outer edges of the tongue members are bowed outwardly adjacent the inner end of the tongue 110 as indicated at 21 to provide a body which may be readily grasped between the thumb

and fingers and whereby the outer portions of the tongues may be overlapped, as will presently be described. The outer side portions of the tongue members are curved inwardly and are rounded into juncture with the ears 10 and 11 forming oppositely opening notches 22 and 23 adapted to interlock with the ends of the slot in the flap; the combined widths of the tongue members between the notches being slightly less than the length of the slot.

Normally the tongue members extend flat and flush with the blank from which they are struck. When it is desired to fasten the flap in its closed position the tongue is raised and the flap turned down to position it beneath the tongue as shown in Fig. 3. One of the tongue members is then advanced a trifle forward of the other. The sides of the tongue members are then gripped between the thumb and forefinger and pinched in such manner as to cause the outer end portions of the tongue members to overlap each other thus contracting the span of the ears so that the outer end of the tongue may be inserted through the slot from the upper side of the flap as shown in Fig. 4.

On releasing the tongue and pressing down on the base portion thereof it will be caused to reassume its flat position with the ears projecting beyond the ends of the slot as indicated in dotted lines in Fig. 2. The flap will then be securely engaged by the fastener and so held by the latter as not to be liable to be accidentally disengaged therefrom; the fastener not being freely detached by reason of the tongue members lying flush with their adjacent edges abutting. When it is desired to detach the fastener it is necessary to dispose the tongue members out of alignment and pinch them into such overlapping position that the ears may be withdrawn from the slot.

From the foregoing it will be seen that I have provided a simple fastener for envelopes, wrappers and the like which may be struck from a blank of paper or similar material and formed either integral with the envelop or wrapper or attached thereto, and that a substantial fastening is produced without employing metallic parts or strings.

While I have shown and described the tongue as formed on the envelop body and the slot as formed in the flap, I may in some instances reverse this arrangement and form the tongue on the flap and the slot in the body. Other modifications may be resorted to in adapting the fastener for use in envelopes or wrappers of various kinds without departing from the invention as

set forth in the appended claims and I accordingly reserve the right to make such changes in form and arrangement as come within the scope of the claims.

I claim:

1. In a fastener for envelopes and the like, a blank, a tongue struck from said blank, a straight score extending along the juncture of the tongue and blank, diagonal scores extending from the ends of said straight score and intersecting on the longitudinal center of said tongue, said tongue formed with a slit extending from the intersection of the diagonal scores and opening at the end of the tongue and dividing the outer portion of the latter into two members adapted to overlap each other, a member having a slot adapted to receive the outer portions of said tongue members, and means on the ends of said tongue members adapted to be engaged by the ends of said slot to connect said member to said tongue.

2. In a fastener for envelopes and the like, a blank, a tongue struck from said blank, a straight score extending along the juncture of the tongue and blank, diagonal scores extending from the ends of said straight score and intersecting on the longitudinal center of said tongue, said tongue formed with a slit extending from the intersection of the diagonal scores and opening at the end of the tongue and dividing the outer portion of the latter into two members adapted to overlap each other, a member having a slot adapted to receive the outer portions of said tongue members, and oppositely projecting ears on the ends of said tongue members adapted to be engaged by the ends of said slot to connect said member to said tongue.

3. In an envelop fastener, a triangular body mounted to swing along one of its edges, a pair of tongue members each mounted to swing on one of the other edges of said triangular body and connected thereto along a fold line, an ear on each of said tongue members, the ear on one tongue member extending in a direction opposite to the ear on the other tongue member, said tongue members being adapted on swinging the triangular body outwardly to be swung inwardly relative to the triangular body to lessen the span of the ear members, the outer edges of said tongue members being bowed outwardly from their intersection with the triangular body, and a member having a slot through which the ears and end portions of the tongue may be passed and the tongues thereafter spread to engage the ears of said member.

LEMUER R. JONES.
